UNITED STATES PATENT OFFICE.

WILLIAM McCONWAY, JR., OF PITTSBURGH, PENNSYLVANIA, ASSIGNOR TO THE
McCONWAY & TORLEY COMPANY, OF PITTSBURGH, PENNSYLVANIA, A CORPORA-
TION OF PENNSYLVANIA.

RAILWAY DRAFT APPLIANCE.

Application filed June 1, 1926. Serial No. 112,975.

This invention relates to draft appliances for railway cars, and has for its object to provide a construction in which a car coupler may be pivotally connected to a draft yoke or its equivalent in such manner that the car can be hauled to its destination in case the connecting pivots or yoke is broken while in service.

The principal feature of the invention resides in associating a car coupler with means pivotally connected thereto for transmitting draft and buffing forces to a cushioning unit, the said means involving a block provided with sockets for receiving trunnions which are integrally united to the coupler and cast in place in said sockets, and the said coupler and block being formed with alined key slots for receiving a draft key, the slot in the coupler being closed at its rear end and elongated to afford clearance between the coupler and the key permitting the former to pivot with respect to the block.

Other features of the invention relating to advantageous combinations of parts and details of construction will hereinafter appear and be pointed out in the claims.

In the drawings illustrating a preferred embodiment of the invention,—

Figure 1 is a view, partly in plan and partly in horizontal section, of a draft appliance embodying the invention, the rear end of the yoke device being omitted.

Figure 2 is a detail view, partly in elevation and partly in vertical section, of the structure shown in Fig. 1.

Figure 3 is a view, partly in plan and partly in horizontal section, of a modified form of the invention.

Figure 4 is a detail view, partly in elevation and partly in vertical section, of the construction shown in Fig. 3.

Figure 5 is a view corresponding to Fig. 3 but illustrating another modified form of the invention.

Figure 6 is a side elevational view of the construction shown in Fig. 5.

In the drawings, 1 is the head and 2 the shank of a car coupler. Adjacent its rear end the shank of the coupler is integrally provided with vertically extending cylindrical trunnions 3, the rear end or bearing face 4 of the shank being curved concentric therewith.

Associated with the coupler is a trun-

nion block 5 having a curved bearing surface 6 for cooperating with the cylindrically curved rear end of the coupler shank. This block is an integral member provided with alined cylindrical sockets 7 for receiving the corresponding trunnions or pivot members 3. Midway between the sockets it is fashioned with a horizontally extending slot 8 for receiving a draft key 9, the said slot being in horizontal alinement with a key receiving slot 10 extending through the coupler shank 1. This last mentioned slot is closed at its rear end and is elongated so that its dimension lengthwise of the coupler is greater than that of the key. The trunnion block 5 is preferably first fashioned and the coupler thereafter cast in place in connected relation therewith.

As shown in Figs. 1 and 2, the trunnion block 5 may be formed as an integral part of a draft yoke having the usual arms 11 for receiving any desired form of followers and cushioning unit (not shown), the forward follower being adapted to cooperate with the flat rear face 12 of the trunnion block 5.

Instead of forming the arms of the yoke device integral with the block 5 as heretofore described, they may be separable therefrom, as indicated at 13 in the construction shown in Figs. 3 and 4, the arms or draft bars 13 shown being such as are employed in the well known Farlow draft attachments. The trunnion block 14 preferably employed in this construction is provided with a forwardly opening key receiving slot 15 instead of a closed one. Other features of this form of the invention being identical with those heretofore described are indicated by corresponding reference numerals.

The construction shown in Figs. 5 and 6 employs a trunnion block 16 cast integral with arms 17 of the yoke device, the construction being in this respect substantially the same as that of Figs. 1 and 2. As in the case of the modified form of the invention just described, the key receiving slot 15 of the block 16 is open at its forward end. The remaining details of construction are identical with those already described and have accordingly been identified by corresponding reference numerals.

The key 9 for use with all forms of the invention is preferably the standard form commonly employed with railway draft at-

tachments. It extends through the slots in the coupler and trunnion block and through the usual slots therefor in the draft sills of the car. Because of the elongation of the key slot 10 in the coupler shank the key may extend therethrough and through the slots of the yoke device and car sills without interfering with the free pivotal movement of the coupler with respect to the yoke. Should the trunnions become broken the car can be hauled to its destination without danger of derailment as the elongation of the slot 10 in the coupler shank enables the coupler to adjust its angular position when the car is passing around curves. In the form of the device shown in Figs. 1 and 2 wherein the key receiving slot of the yoke device is closed at its forward end, the key 9 serves to connect the coupler to the yoke in the event the trunnions 3 are broken. Similarly, in the construction shown in Figs. 3 and 4, the key 9 serves to connect the coupler to the Farlow draft links 13 if the trunnions 3 are broken in service. The form of construction illustrated in Figs. 5 and 6 is advantageous in that should the yoke straps 17 become broken they can be cut off flush with the rear face of the trunnion block 16; and the latter, together with the coupler 2, may be made use of in the manner illustrated in Figs. 3 and 4, considerable loss of material thereby being avoided. The construction is such that the key 9 may be initially associated with the remaining parts of the mechanism.

I claim:—

1. A railway draft appliance comprising a car coupler, and means pivotally associated therewith for actuating a cushioning unit, said coupler and means having trunnion and socket engagement formed by a

plurality of integrally connected trunnions cast in place in the corresponding sockets and also having alined key receiving slots, the slot in said coupler extending the greater distance rearwardly and being closed at its inner end. 45

2. A railway draft appliance comprising a car coupler, and means pivotally connected thereto for actuating a cushioning unit, said means including an integral block formed with trunnion sockets, said coupler having integrally attached trunnions extending into the corresponding sockets of said block, and the coupler and block being slotted to receive a draft key, the slot in said coupler being closed at its rear end. 50

3. A railway draft appliance comprising a car coupler, and means for transmitting draft forces therefrom to a cushioning unit, said means involving a yoke device, a block pivotally connected to said coupler, and a key operatively connecting said block and yoke device, said block being provided with trunnion sockets, the coupler being integrally formed with trunnions extending into the sockets and the coupler being slotted to receive the key, the said slot in the coupler being elongated to afford clearance for the key permitting the coupler to pivot with respect to the block. 65

4. A railway draft appliance involving a car coupler provided at its rear end with a key slot and having a plurality of integrally united trunnions, and a block provided with sockets for receiving said trunnions, the block being formed with a forwardly opening slot, and said slots in the coupler and block being in horizontal alinement and adapted to receive a draft key. 75

In testimony whereof I affix my signature.
WILLIAM McCONWAY, JR.
